LEVER FOR SCREW DRIVERS

Edward L. Clarke, Scranton, Pa.

Application August 2, 1946, Serial No. 687,855

2 Claims. (Cl. 145—65)

1

My invention relates to improvements in screw drivers and the like, and has for its primary object to provide novel and improved lever means which is readily attachable to the screw driver shank so that great leverage can be applied for starting an over-tightened screw.

It is also an object of the invention to provide a screw driver having an anti-friction handle piece and a detachable shank-actuating lever whereby turning leverage can be readily applied to the tool while maintaining it centered with the work.

Another object of the invention is to provide a screw driver attachment, as characterized, which is very simple in construction, economical to manufacture, and which can be readily applied to the screw driver shank, as the occasion may require.

Additionally, the invention contemplates a device of this kind which incorporates at least one removable handle portion, the advantage of such arrangement being that when working adjacent a wall, leverage can be applied to the screw driver shank while still maintaining the screw driver perpendicular to the work. It is also apparent that the use of one laterally extending handle will enable the shank to be turned approximately 180° at a time.

Having in mind the preceding paragraph, a prime advantage of the preferred form of my invention is that the removable laterally extending handle can be detached from the assembly leaving the other handle gripped to the screw driver shank; and when it is desired to use both laterally extending handles the removable one can be replaced while the other is still clamped to the screw driver shank.

Other objects and advantages of the invention will be understood and appreciated by mechanics upon reference to the accompanying drawing, in connection with the detailed description which follows.

In the drawing, wherein the same reference characters have been used to designate the same parts throughout the several views—

Fig. 1 is a side elevational view of a screw driver embodying my invention;

Fig. 2 is a cross sectional view through the screw driver illustrated in Fig. 1, the view having been taken on the line 2—2 of Fig. 1, so as to show the lever attachment in plan;

Fig. 3 is a cross sectional view taken on the line 3—3 of Fig. 2;

Fig. 4 is a perspective view of a clamp block which is incorporated in the lever attachment;

2

Fig. 5 is a fragmentary perspective view illustrating the removable handle element and its clamping means; and

Fig. 6 is a view similar to Fig. 5 but with the parts separated slightly.

Referring to the drawing, by reference characters, numeral 6 designates the shank of what may be a conventional screw driver, the end of the shank having the usual kerf-engaging

blade 6a.

Adjacent the reduced inner end of the handle 6c of the screw driver, the shank thereof is squared or otherwise flat-faced, as indicated at 6b. The object of this flat-faced formation 6b is to non-rotatably receive opposed clamp element recesses 7, of the lever attachment, which will now be described.

By preference, the flat-faced or squared shank portion 6b will be raised slightly from the adjacent surface of the shank 6 so that the clamp can be slid off readily when loosened. However, this raising of the flat-faced clamp engaging portion is to be regarded as optional because, of course, when the handle, incorporating clamp 15 is applied to an ordinary screw driver, production of the flat-surfaced portion 6b of the shank thereof, will necessarily be accomplished by filing or milling away a part of the shank.

Coming now to the novel handle incorporating 30 clamp, it will be seen that the same comprehends the rectangular block 8 and the matching inner end portion 9 of a laterally extending handle 9a.

Fig. 3 illustrates the opposed matching portions of the block 8 and handle 9, 9a, as being 35 provided with lineally extending recesses 8a, 9b, respectively, disposed in opposition to one another. In the present instance, these recesses 8a, 9b, are depicted as being of rectangular cross section and as receiving the similarly formed inner end 10, 40 of a removable handle 10a, which projects laterally from the opposite side of the shank from the handle 9a.

As best shown in Fig. 2, the members 8, 9 are 45 provided with opposed V-shaped notches 7, which are adapted to receive the squared or flattened shank portion 6b, so that when the parts 8, 9, are clamped together, the shank 6, 6b will be non-rotatably assembled therewith.

Means, in the form of wing headed clamp screws 50 or the like 11, are availed of for clamping the block 8 and handle end 9 together. Fig. 2 of the drawing illustrates one clamp screw 11 as extending through a hole 13 in block 8 and threaded into the aligned threaded hole 14 in the block-like end 9 of lever or handle 9a. The other clamp

screw 11 is inserted through a hole 14a in the block-like handle end 9, and threaded into an aligned hole 13a in the opposed block 8. Of course the wing heads of screws 11 can both be at the same side of the device if desired.

In the case of the clamp screw 11 which is adjacent the removable handle 10, 10a, it may, and preferably does, go through a hole in the squared end 10 of said removable lever or handle 10a.

Of course clamp screws 11, of other than the "wing" headed type may be used, such as those having lineally serrated heads.

As will be understood from Figs. 2 and 3, removal of the associated clamp screw 11 is necessary when lever 10, 10a is to be removed. However, if the squared end 10 of the removable lever 10a terminates short of the adjacent clamp screw 11, the removable handle 10a, 10 can be pulled out after simple loosening said adjacent screw 11. In either event, however, removal of handle 10, 10a enables the screw driver to be used in the manner of a wrench, when available working space is limited. Even if screw 11 goes through the end 10 of the handle 10a, the latter can be removed by removing the screw 11. The companion screw 11 on the opposite side of the shank 9 will keep the clamps 8, 9 in assembly with the screw driver shank 6.

Manipulation of the screw driver, embodying my invention, is greatly facilitated by the reason of the rotatable palm support 15, at the outer end of the handle 6c, as shown in Fig. 1. This rotatable palm grip, in the illustrated form of the invention, is indicated as a preferably friction annulus 15, seated in the peripheral U-shaped groove 15a of a hub 15b. The hub is rotatably secured to the end of the handle 6 by means of the concentric screw or pin 16.

From the foregoing description, read in connection with the drawing, the construction and advantages of the invention will be readily understood. Although I have illustrated herein what appears to be a preferred example of the invention, it will nevertheless be realized that it may take other form without departing from the spirit and scope of the subject matter claimed hereininafter.

Having thus described my invention, what I claim as new is:

1. A lever attachment for screw driver shanks comprising in combination a first laterally extending handle terminating at its inner portion in a clamping block-like end and having a lineally

extending recess therein and also having a V-shaped groove formed in one face thereof, said block-like end having spaced screw receiving openings extending transversely therethrough, a rectangular clamping block element spaced opposite to the block-like end of the handle, said rectangular block element having a V-shaped groove in its face and having a lineally extending recess and spaced screw receiving openings, a second laterally extending handle having a flattened inner end fitting within the opposed lineally extending recesses of the clamping block and clamping block-like handle end, the inner end of said second handle having an opening therethrough, and wing headed screws extending through the spaced openings of the handle end and the rectangular block, one of the screws passing through the opening in the removable handle member, thereby to clamp the oppositely disposed handles to the screw driver shank.

2. A lever attachment for screw driver shanks comprising in combination a first laterally extending handle terminating at its inner portion in a rectangular shaped clamping block having a lineally extending recess therein and further provided with spaced screw receiving openings and a V-notch for receiving the shank of a screw driver, a second cooperating clamping block having a lineally disposed recess therein oppositely disposed with respect to the recess of the first-mentioned clamping block, said second block having spaced screw receiving openings and a V-notch therein, a second laterally extending handle provided with a flattened end for fitting the lineally disposed recesses of the clamping blocks, and an opening in the said handle end, and screws extending through the screw receiving openings in the opposed clamping blocks, one of the screws engaging the opening in the end of the second handle.
